The ornamental design for a display screen or portion thereof with graphical user interface, as shown and described.

DESCRIPTION

FIG. 1 is a front view of a display screen or portion thereof with graphical user interface showing our new design; FIG. 2 is an enlarged view thereof shown in two parts, 2A and 2B; and,

FIG. 3 is an enlarged view of a portion of FIG. 1.

The outermost dashed broken lines in the Figures show a display screen or portion thereof, and form no part of the claimed design. The other dashed broken lines in the Figures show portions of the graphical user interface that form no part of the claimed design. The dot-dash broken lines in the Figures show a boundary that forms no part of the claimed design. The dot-dot-dash lines in FIGS. 2A and 2B show the location at which FIG. 1 has been divided for ease of illustration and form no part of the claimed design.
